[57] **CLAIM**

The ornamental design for the transparent top opaque bottom flexible beverage container, as shown and described.

DESCRIPTION

FIG. 1 is a front perspective view of my design for a transparent top opaque bottom flexible beverage container showing the characteristic feature of the design, which resides in its shape together with having a transparent upper portion and an opaque lower portion on the front and back. FIG. 2 is a top view thereof.

FIG. 3 is a bottom view thereof.

FIG. 4 is a front elevational view thereof.

FIG. 5 is a right side elevational view thereof, the left side is identical; and,

FIG. 6 is a rear elevational view thereof.
